(57) **CLAIM**

The ornamental design for a point-of-sale-activation device, as shown and described.

DESCRIPTION

FIG. 1 is a perspective view of a point-of-sale-activation device of the present invention;

FIG. 2 is a top view of the point-of-sale-activation device shown in FIG. 1;

FIG. 3 is a right side view of the point-of-sale-activation device shown in FIG. 1;

FIG. 4 is a bottom view of the point-of-sale-activation device shown in FIG. 1;

FIG. 5 is a left side view of the point-of-sale-activation device shown in FIG. 1;

FIG. 6 is a back view of the point-of-sale-activation device shown in FIG. 1; and,

FIG. 7 is a front view of the point-of-sale-activation device shown in FIG. 1.
